UNITED STATES PATENT OFFICE.

WILLIAM F. STELLNER, OF DANVILLE, ILLINOIS.

TRAFFIC SIGNAL.

Application filed October 12, 1922. Serial No. 594,021.

To all whom it may concern:

Be it known that I, WILLIAM F. STELLNER, a citizen of the United States, residing at Danville, in the county of Vermilion and 5 State of Illinois, have invented certain new and useful Improvements in Traffic Signals, of which the following is a specification.

This invention relates to traffic signals and it consists in the novel features hereinafter 10 described and claimed.

An object of the invention is to provide a signal of the character stated which is of simple and durable structure and which may be easily and quickly set up or removed 15 from a roadway or street as desired.

While the device is primarily intended as a traffic signal it may be used to advantage for other purposes as for instance "Safety first sign," "Quiet zone," "Hospital," "School 20 house," "Danger," "Drive slow," "No parking," "Street names," and the like.

When used as a traffic directing or controlling sign the signal is provided with the usual words "Stop" and "Go."

25 The signal structure comprises a socket member which is permanently planted in the circuit portion of a street or roadway. A shaft or standard is slidably received in the socket member. This shaft is provided with

30 a collar which closes the upper end of the socket member. A traffic signal casing A is revolvably mounted on the upper end of the shaft and is provided with angularly disposed side surfaces upon one of which ap-

35 pears the word "Stop" and upon an adjacent surface appears the word "Go" when the signal is used for controlling the movement of traffic. In use the officer or director stands at the side of the signal and faces in

40 the direction from which the vehicles are approaching. With one hand he turns the signal casing to bring an intended legend of instruction to view to the occupant of an approaching vehicle and he may with the 45 other hand indicate the direction in which the vehicle is to proceed.

In the accompanying drawing:—

Figure 1 is a side elevation of the traffic signal with parts broken away and parts in 50 section.

Figure 2 is a horizontal sectional view of the signal casing, and Figure 3 is a fragmentary vertical sectional view of the same.

As illustrated in the accompanying drawings, the signal structure comprises a socket member 1 which is closed at the bottom and

open at the top. The socket member is adapted to be planted or mounted in the circuit portion of a street or roadway, in any suitable manner, and as indicated in Figure 60 1 of the drawing, with its open end flush with the surface of the street or roadway. The signal structure further includes a shaft 2 whose lower end is received by the socket member 1. A shoulder 3 is formed upon the 65 lower end of the shaft 2 and the upper end of the socket 1 when the shaft is in position in the latter. A shoulder 4 is formed upon the upper intermediate portion of the shaft 2 and a traffic signal casing 5 is revolvably 70 mounted upon the upper end of the shaft 2. The casing 5 is provided with angularly disposed side surfaces or panels 6 and each of the said panels bears a visible sign or legend 75 7 as for instance the word "Stop" and "Go" as illustrated in Figure 1 of the drawings. Other signs or legends may be employed if desired or required. The upper end of the casing 5 is pointed, as at 8, to shed the rain and the sign legends are set back from the 80 corner portions of the casing 5 in order that they may not be obscured by rain, snow or sleet.

The casing 5 is provided with a central tubular sleeve 9 which receives and turns on 85 the upper end of the shaft 2. The lower end of this sleeve extends about six inches below the bottom of the casing and provides a convenient hand hold to be grasped by the operator in turning the casing. The lower end 90 of the sleeve 9 bears against and works upon the shoulder 4.

The device is installed by planting the socket 1 in the road or street as hereinbefore described and by slipping the lower end of the shaft 2 into the socket. Thus the shaft is held in a vertical position and the officer may turn the signal casing to bring any particular legend of the signal to the view of the driver of an approaching vehicle. 100 When no use is required for the signal the shaft 2 is lifted out of the socket member 1 and the shaft and casing are removed from the roadway or street, leaving the socket member planted in position and ready to 105 receive the shaft again when the use of the signal is again required. In view of the fact that the upper end of the socket is flush with the surface of the street it presents no obstruction or interference to the 110 movement of street traffic when the shaft is removed therefrom.

Having described the invention, what is claimed is:

In a signal structure, a socket member open at its upper end, a vertical shaft or standard whose lower end is received by said socket member, a shoulder formed on the upper intermediate portion of said standard and a traffic signal casing having a central tubular sleeve receiving and revolvably

mounted on the upper end of the standard, 10 the lower end of the sleeve extending below the bottom of the casing and working on said shoulder said downwardly projecting portion of the sleeve forming a hand hold adapted to be used by the operator in turning the 15 signal casing.

In testimony whereof I affix my signature.
WILLIAM F. STELLNER.
